UNITED STATES PATENT OFFICE.

THEODORE E. ERDMANN, OF MINNEAPOLIS, MINNESOTA.

MOLD FOR CONCRETE WALLS.

Application filed July 10, 1922. Serial No. 574,096.

To all whom it may concern:

Be it known that I, THEODORE E. ERDMANN, a citizen of the United States, residing at Minneapolis, in the county of Hennepin and State of Minnesota, have invented certain new and useful Improvements in Molds for Concrete Walls, of which the following is a specification.

My invention relates to forms for concrete construction and more particularly to forms for conveniently and rapidly putting up hollow walls or partitions.

The object is to provide a simple device by means of which a concrete wall, whether single or double, can be built up in horizontal layers, the device being moved as fast as the hardening of the concrete will permit.

In the accompanying drawings;

Fig. 1 is a top view of two of my devices, one for straight walls and the other for corners of walls, showing them applied on a wall in the process of being built and the wall being of the hollow type.

Fig. 2 is an enlarged top view of the right hand portion of the straight wall device in Fig. 1.

Fig. 3 is an enlarged sectional elevation as on line 3—3 in Fig. 1 and comprises also an end view of Fig. 2 with the concrete wall added.

Fig. 4 is an enlarged sectional detail as on line 4—4 in Fig. 3.

Fig. 5 is a detail elevation of the sliding beam levers illustrated in Fig. 3 but seen from the opposite side and omitting the lower integral parts thereof.

Fig. 6 is an enlarged sectional elevation about as on line 6—6 in Fig. 1, the wall being omitted.

Fig. 7 is an enlarged sectional elevation as on line 7—7 in Fig. 6.

Fig. 8 is an enlarged sectional view as on line 8—8 in Fig. 3.

Fig. 9 is a side elevation of one end of the straight wall building part of my invention slightly modified for building up walls with slanting edges for gables and similar purposes.

It will first be noted that my device comprises primarily, means for building hollow concrete walls; straight walls and corners alike being built up on the same principle viz; a hollow collapsible core and an outer and inner wall, all held together in parallel spaced relation while the concrete is poured,

and readily removable by means to be described, when the concrete has hardened enough to permit such removal.

Referring to the drawing by reference numerals, 10 is the foundation of a building upon which a hollow wall comprising parallel wall members 11 with a continuous air space 12 between them. The only element traversing said air space is preferably a number of cross bars 13 laid across said space and in the top surface of the previously laid layer of concrete, to provide a rest for my device (see Figs. 1 and 3).

My device comprises, for straight wall building, an elongated frame with an outwardly opening, horizontally arranged, channel shaped member 14, a similar inwardly opening member 15 spaced parallel to member 14, and a central, elongated, collapsible core 16—17 which are identical channel members with their flanges normally in overlapping relation (see Figs. 2, 3 and 6).

The upper flange of channel 14 is flared, as 14^x in Fig. 3, and channel 15 is likewise flared, as 15^x, to facilitate the pouring of concrete into the mold.

Each frame section has its wall members 14, 15, 16 and 17 connected respectively by vertical bars 18, 19, 20 and 21 secured to their respective web portions by yokes 22, said bars having each a horizontal upper end secured to a transversely arranged beam above the channel members and which will now be described.

Each beam comprises two slidably connected parallel bars 23—23^x (see Figs. 3 and 5) connected by shoulder bolts 24—25 both having countersunk heads. The bolt 24 (at left in Figs. 2 and 3) is secured in bar 23 and is slidable in a horizontally arranged slot 26 in bar 23^x and carries a collar 27 between the nut 28 and its shoulder adjacent the bar 23^x. Bolt 25 is secured in the opposite end of the beam in bar 23^x and engages in a similar slot 29 in bar 23 and is held in place by a nut 30.

In Fig. 4 I have shown one of the yokes 22 securing bar 18 to channel member 14 by means of a cotter pin 31 inserted in registering apertures in the yoke and the bar.

In Figs. 2, 3 and 5 is best shown how the frame bars 19—20 have their horizontal portions secured to the beam section 23 by bolts 32 and 33, respectively, the channel mem-

bers 15 and 16 thus being held in permanent spaced relation, whereas bolts 34 and 35 secure the upper ends of the bars 18 and 21 to beam section 23^x and holding the channel members 14 and 17 respectively, fixed in proper spaced relation. Bar 19 has its horizontal portion extended inwardly and at its inner end I fulcrum at 36 a hand lever 37 (see Figs. 1, 2, 3 and 5) and at a certain 10 predetermined point as 38, on said lever 37 I secure pivotally one end of a connecting rod 39 whose other end is pivotally secured on the previously described shoulder bolt 35 secured in beam member 23^x. Thus the fulcrum end of the hand lever is directly connected to the beam 23 and its channel members 15 and 16 and the connecting rod 39 is directly connected to beam member 23^x and its channel members 14 and 17. In Fig. 3 15 the hand lever position (in full lines) shows the channel members in position to permit pouring of concrete, the fulcrum 36 of the lever being higher than the pivot bolt 38 of the connecting rod 39, the latter locks the 20 whole device on the toggle-joint principle. 25

After the concrete has been poured in the mold thus formed, and begins to harden, the operator merely raises the levers 37 of the device to approximately the position 30 shown dotted in Fig. 3. This movement of the hand lever causes the beam members 23-23^x to slide horizontally in opposite directions, because of the pulling force at fulcrum 36 and the pushing of connecting rod 39. Consequently the parallel wall members 14-15 are spread away from the wall 35 and the collapsible core members 16 and 17 are sprung toward each other and the device 40 is sprung away from all the newly formed wall surfaces and can be moved along horizontally to make the next section of wall.

My invention is also applicable to corner construction of walls and the device, as made for such places, is illustrated to the left in 45 Fig. 1 and more in detail in Figs. 6 and 7. Instead of straight frames connected by two or more beams I provide angularly arranged, spaced wall and core sections and only one operating beam and hand lever, 50 all of similar construction to the parts already described, all the similar parts used in said corner frame illustrated in Figs. 1, 6 and 7 carrying the same numbers but with the exponent "a," to avoid confusion. 55 The frame channels and adjustable beams, it will be noted, are in this case connected by vertical posts of angle iron the vertical posts flattened at their horizontal parts. The beam of the corner frame is preferably 60 made of two angle irons 23^a, 23^x, placed back to back and their upper legs forming a flat surface on which a spirit level 40 may be placed to determine when the device is in proper position. The same construc-

tion may, of course, also be used on the 65 straight wall frames.

To provide for angular wall ends registering apertures 41 are made in the lower end portions of the frame channels 14 and 15 and the collapsible core channels 16-17 (see 70 Figs. 3 and 9) and a rod 42 is engaged therein. On said rod are fulcrumed the lower ends of two boards 43, each as wide as the space between the frame wall members 14-15 and the core. The angle of each 75 board is fixed by a rod 44 pivotally secured with one end, as at 45, to the board, the other end of the rod being slidable in a slot 47 of a bracket 46 fixed on the beam member 23 and having a thumb screw 48 adapted to 80 engage the rod within the slot. Having set the board or boards 43 at the desired angle, concrete is filled in the acute-angle space thus formed under the board or boards. 85

In Fig. 8 I have shown how the overlapping flanges of the collapsible core channels 16-17 have clearances 49 and 50 respectively, for the respective bars 20 and 21 to slide into when the core is sprung together previous to removing the frame from a finished 90 wall section.

The operation of my device being already fully disclosed in the specification it is only necessary to call attention to the fact that 95 with my device no extra tools are required and no loose, special parts need be carried around, each device being complete in itself and, if properly made, is comparatively light and always easily set in place for the successive pourings of concrete. 100

What I claim is;

1. In a device of the class described, having spaced walls and an intermediate collapsible core and adapted to receive a concrete filling between them, adjustable means 105 between said core and the walls to permit filling of concrete to a predetermined angular line.

2. The structure specified in claim 1, said adjustable means comprising a vertically swingable partition between each wall and the core, a removable hinge bar transversely arranged in apertures in and adjacent the bottom of the core and wall channels, a hinge member at the bottom end of each partition and adapted to pivotally engage said bar, and means pivotally secured to each partition, above its hinge, to set the same at any desired angle. 110

3. The structure specified in claim 2, said means for holding the partition comprising a rod pivotally secured to the partition, a fixed post on the beam slotted to slidably receive said rod and a set screw in the post to engage the rod within the slotted portion 115 of the post. 120

In testimony whereof I affix my signature.

THEODORE E. ERDMANN.
